(57) **CLAIM**

I claim the ornamental design for the vacuum actuated clothes-lint shaver, as shown and described.

DESCRIPTION

The present design relates to a clothes-lint shaver adapted to frictionally and releasably attach to a conventional vacuum cleaner hose end wherein the central body portion contains an impeller rotably connected to the shaving blades of the clothes-contacting portion through which a flow of air created by a vacuum cleaner propels the impeller.

FIG. 1 is a perspective view from above of the vacuum actuated clothes-lint shaver of the present design.

FIG. 2 is a right side cross-section view taken along lines 2—2 of FIG. 5 of the vacuum actuated clothes-lint shaver of the present design.

FIG. 3 is a right side elevation view of the vacuum actuated clothes-lint shaver of the present design.

FIG. 4 is a left side elevation view of the vacuum actuated clothes-lint shaver of the present design.

FIG. 5 is a top plan view of the vacuum actuated clothes-lint shaver of the present design.

FIG. 6 is a bottom plan view of the vacuum actuated clothes-lint shaver of the present design.

FIG. 7 is a rear elevation view of the vacuum actuated clothes-lint shaver of the present design; and,

FIG. 8 is a front elevation view of the vacuum actuated clothes-lint shaver of the present design.
